(57) **CLAIM**

The ornamental design for an insulating device, as shown and described.

DESCRIPTION

FIG. 1 is a top, front, left perspective view of an insulating device showing our new design in an open configuration; FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a top, front, right perspective view of an insulating device showing our new design in a closed configuration; FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

The uneven-length broken lines represent unclaimed boundaries of the claimed design. The even-length broken lines showing the remainder of the insulating device represent unclaimed subject matter and form no part of the claimed design.
